UNITED STATES PATENT OFFICE.

LEE J. BLACK AND ERNEST E. SWOPE, OF BEAUMONT, TEXAS.

SCREW PUMP.

Application filed September 16, 1926. Serial No. 135,871.

This invention relates to screw pumps and more particularly to a device of this character employing opposed screws as a means for generating water pressure.

5 An important object of the invention is to provide a device of this character wherein the screw may be readily replaced and wherein the mountings of the screw are readily accessible for removal or repair.

10 A further object of the invention is to provide the chamber in which the screw operates with a removable liner and a novel means whereby this liner may be packed to prevent leakage thereabout.

15 A still further object of the invention is to provide a liner within which the screw operates including a baffle against which the stream generated by the opposed worms impinges, so that its circulatory motion is broken up and it is directed into the outlet.

20 A still further object of the invention is to generally improve the structure of this type of pumps, so that they may be more readily and cheaply manufactured and more readily repaired.

25 These and other objects we attain by the construction shown in the accompanying drawings, wherein for the purpose of illustration is shown a preferred embodiment of our invention and wherein:

Figure 1 is a longitudinal sectional view through a pump constructed in accordance with our invention;

Figure 2 is a central transverse sectional view therethrough.

Referring now more particularly to the drawings, the numeral 10 generally designates a pump barrel having removable heads 11 at opposite ends thereof. Within the barrel, a liner support 12 is maintained in spaced relation to the walls of the barrel and has its ends spaced from the adjacent heads 11. The central portion 13 of this liner support has a hexagonal bore, while the ends thereof have a circular bore 14 equal to the circumscribed diameter of the hexagonal bore 13. A liner 15 is provided in the form of a sleeve, the exterior of which is hexagonal at its central portion 16 and fits within the hexagonal portion 13 of the bore of the liner support. The ends of the liner are exteriorly rounded and oppose the walls of the circular bore of the liner support in spaced relation thereto to provide a packing space 17. These packing spaces appear at each end of

the liner and are properly filled with packing upon which is placed a follower ring 17 which may be adjusted toward the center of the liner support by adjusting screws 18 threaded through the heads 11 and held in position by lock nuts 19. The heads 11 are each provided with a bore 20 co-axial with the bore of the liner and through this bore extends a packing gland 21 having at its inner end a flange 22 abutting the inner face of the associated head through a lead or other suitable gasket, indicated at 23. The outer end of the gland is exteriorly threaded at 24 for the reception of a lock nut 25, by means of which the flange of the gland may be drawn tightly against the gasket 23. These threads likewise serve to provide the mounting for a cap 26 by means of which the gland follower 27 is moved inwardly against the packing 28.

These glands rotatably support the smaller outer ends 29 of a shaft 30. The shaft has an enlarged central portion 31 and between this central portion and the outer ends 29 an intermediate portion 32 upon which the worms 33 are mounted. The shoulders 34 produced upon the shaft between the enlarged central portion 31 and intermediate portions 32 provide limits regulating the approach of worms 33 toward the center of the shaft and the shaft has threaded portions 35 for mounting lock nuts 36 which serve to maintain the worms against these shoulders. The worms are suitably keyed to the shaft, as at 37. The liner 15 is provided centrally with an inwardly projecting flange 38 extending adjacent the surface of the enlarged portion 31 of the shaft. This flange is slotted at 39 to provide a passage which is directed outwardly toward an outlet opening 40 which is projected through the liner carrier and the outer wall of the worm, as indicated. The worms 33 are preferably produced upon trunco-conical cores 41, the base or larger ends of which abut the shoulders 34 and oppose the flange 38. These base ends are of slightly less diameter than the bore of the liner at the large ends thereof and have produced thereon a worm thread 42 which comes into close contact with the inner wall of the bore throughout its length. Since the space between the face of the core and the wall of the bore decreases toward the center of the liner, it will follow that fluid passing between the worms will be 110

compressed during its passage and accordingly under considerable pressure when it reaches the flange 38. The face of the worm in its coaction with the flange acts more or less as a valve alternately cutting off and permitting communication between the fluid space and the opening 39, thus permitting the pressure to build up to a still higher point. The inner end of the slot 39 is aligned 5 with the adjacent ends of the cores 41, so that the formation about the shaft between these cores of a dead water space is effectually prevented. The walls of the opening 39 further serve to break up the 10 tendency of fluid received from the worm to rotate and direct this fluid to the outlet. It will, of course, be understood that fluid entering the barrel of the pump will fill the space within the barrel and enter at the 15 outer ends of the worms.

A pump of this character may be very readily assembled or disassembled when any repairs are necessary. If, for example, it is necessary to renew the screws and liners, 20 it is merely necessary to unbolt the heads 11 and remove them from the body of the pump. This will release the worms 33 and glands 17 and the packing may be pulled from about the liners. The entire liner, 25 with its assemblage of the shaft and worms, may then be bodily withdrawn from the pump for repair. To remove the liner from the shaft, it is then merely necessary to remove one of the worms 33. Out-bearings 43 30 may be provided for the projecting ends of the shaft and where provided, these will be carried by the heads 11, so that they may be removed therewith.

It will be obvious that the construction 35 hereinbefore set forth is capable of a certain range of change and modification without materially departing from the spirit of the invention and we accordingly do not limit ourselves to such specific structure except as 40 hereinafter claimed.

We claim:—

1. In a screw pump, a barrel having heads 45 at least one of which is removable, a shaft rotatably directed through said heads, a liner support within the barrel and surrounding the shaft, a liner sleeve supported by the liner support and likewise surrounding the shaft and having engagement with the support centrally thereof whereby it is 50 held against rotation with relation to the support, the adjacent faces of the end portions of the sleeve and support being spaced to provide packing spaces, followers engaged in the ends of the packing spaces, 55 means adjustable through said heads for shifting the followers and spaced opposed worms mounted upon the shaft within the sleeve.

2. In a screw pump, a barrel having heads 60 at least one of which is removable, a shaft

rotatably directed through said heads, a liner support within the barrel and surrounding the shaft, a liner sleeve supported by the liner support and likewise surrounding the shaft and having engagement 70 with the support centrally thereof whereby it is held against rotation with relation to the support, the adjacent faces of the end portions of the sleeve and support being spaced to provide packing spaces, followers 75 engaged in the ends of the packing spaces, means adjustable through said heads for shifting the followers, spaced opposed worms mounted upon the shaft within the sleeve, the barrel having an inlet and an outlet, the outlet communicating with the space between the worms, the inlet communicating with the ends of the sleeve and means supported by the sleeve and surrounding the shaft between the worms preventing rotation 80 of fluid about the shaft at the outlet and directing the fluid to the outlet.

3. In a screw pump a barrel having heads at least one of which is removable, a shaft rotatably directed through said heads, a liner support within the barrel and surrounding the shaft, a liner sleeve supported by the liner support and likewise surrounding the shaft and having engagement 90 with the support centrally thereof whereby it is held against rotation with relation to the support, the adjacent faces of the end portions of the sleeve and support being spaced to provide packing spaces, followers 95 engaged in the ends of the packing spaces, means adjustable through said heads for shifting the followers, spaced opposed worms mounted upon the shaft within the sleeve, the barrel having an inlet and an outlet, the outlet communicating with the space between the worms, the inlet communicating with the ends of the sleeve, means supported by the sleeve and surrounding the shaft between the worms preventing rotation 100 of fluid about the shaft at the outlet and directing the fluid to the outlet comprising a flange having an opening for the passage of the shaft and a radial notch communicating with the outlet.

4. In a screw pump, a barrel having heads 115 at least one of which is removable, a shaft rotatably directed through said heads, a liner support within the barrel and surrounding the shaft, a liner sleeve supported by the liner support and likewise surrounding the shaft and having engagement with the support centrally thereof whereby it is held against rotation with relation to the support, the adjacent faces of the end portions of the sleeve and support being spaced to provide packing spaces, followers 120 engaged in the ends of the packing spaces, means adjustable through said heads for shifting the followers and spaced opposed worms mounted upon the shaft within the sleeve.

125 5. In a screw pump, a barrel having heads at least one of which is removable, a shaft

sleeve, adjacent ends of said worms having engagement with the liner preventing longitudinal movement thereof.

5. In a screw pump, a barrel having heads at least one of which is removable, a shaft rotatably directed through said heads, a liner support within the barrel and surrounding the shaft, a liner sleeve supported by the liner support and likewise surrounding the shaft and having engagement with the support centrally thereof whereby it is held against rotation with relation to the support, the adjacent faces of the end portions of the sleeve and support being spaced to provide packing spaces, followers engaged in the ends of the packing spaces, screws adjustably directed through said heads and having their inner ends abutted against the adjacent follower and spaced opposed worms mounted upon the shaft within the sleeve.

6. In a screw pump, a barrel having heads at least one of which is removable, a shaft rotatably directed through said heads, a liner support within the barrel and surrounding the shaft, a liner sleeve supported by the liner support and likewise surrounding the shaft, said support and sleeve having coacting polygonal central portions engaging to prevent relative rotation thereof, the ends of the opposed faces of the support and sleeve being circular and being spaced from one another to provide annular packing spaces, follower rings inserted in the ends of the packing spaces, means adjustable through the heads and engaging the packing rings and spaced opposed worms mounted upon the shaft within the sleeve.

7. In a screw pump, a barrel having heads at least one of which is removable, a shaft rotatably directed through said heads, a liner support within the barrel and surrounding the shaft, a liner sleeve supported by the liner support and likewise surround-

ing the shaft, said support and sleeve having coacting polygonal central portions engaging to prevent relative rotation thereof, the ends of the opposed faces of the support and sleeve being circular and being spaced from one another to provide annular packing spaces, follower rings inserted in the ends of the packing spaces, means adjustable through the heads and engaging the packing rings and spaced opposed worms mounted upon the shaft within the sleeve, the sleeve having a central flange one edge of which is extended into proximity to the shaft, said flange having a radially directed notch.

8. In a screw pump, a barrel having heads at least one of which is removable, a shaft rotatably directed through said heads, a liner support within the barrel and surrounding the shaft, a liner sleeve supported by the liner support and likewise surrounding the shaft, said support and sleeve having coacting polygonal central portions engaging to prevent relative rotation thereof, the ends of the opposed faces of the support and sleeve being circular and being spaced from one another to provide annular packing spaces, follower rings inserted in the ends of the packing spaces, means adjustable through the heads and engaging the packing rings and spaced opposed worms mounted upon the shaft within the sleeve, the sleeve having a central flange one edge of which is extended into proximity to the shaft, said flange having a radially directed notch, said worms having frustro-conical cores the larger ends of which are opposed to the flange, the base of the notch aligning with the adjacent edge of the core.

In testimony whereof we affix our signatures.
